SOY BEAN CRUSHER

Henry Ford and Robert A. Boyer, Dearborn, Mich.,
assignors to Ford Motor Company, Dearborn,
Mich., a corporation of Delaware

Application November 1, 1937, Serial No. 172,108

2 Claims.

(Cl. 83—9)

The object of our invention is to provide a crusher especially adapted for crushing soy beans in preparation for the extraction of the oil therefrom.

Specifically our invention comprises a machine having a pair of rolls therein which are adapted to rotate together at a relatively high peripheral speed and between which the beans are crushed. The novel feature of this invention is that the beans are flattened in such manner that each individual bean requires about 45 degrees of rotation of the rollers to flatten same. This produces a much longer duration for crushing than would occur in a conventional roller type crusher having a roller diameter many times that of the device disclosed herein. For this reason the power required to operate our improved machine is considerably less than that required to operate other types of crushers of equal capacity.

With these and other objects in view our invention consists in the arrangement, construction and combination of the various parts of our improved device, as described in our specification, claimed in our claims, and illustrated in the accompanying drawing, in which:

Figure 1 is a side elevation of our improved crusher, a portion thereof being broken away through the center line of the rolls to better illustrate the construction.

Figure 2 is a sectional view, taken upon the line 2—2 of Figure 1.

Figure 3 is a sectional view, taken upon the line 3—3 of Figure 1, and

Figure 4 is a diagrammatic view illustrating the means for feeding the beans into the crusher and for deflecting the flakes therefrom.

Referring to the accompanying drawing we have used the reference numeral 10 to indicate the base plate upon which our machine is constructed. A pillow block 11 is secured to the plate 10 at one end thereof, said block having a shaft 12 rotatably mounted therein. A pulley 13 is secured to the shaft 12 adjacent to one end of the base plate 10, while a roller 14 is formed integrally with the inner end of the shaft 12.

Adjustably mounted upon the other end of the plate 10 we have provided a bracket 15 which is bolted thereto. A pivot pin 16 is fixed to the bracket 15 and a bearing block 17 is pivotally secured to the pin 16. The block 17 is provided with a driven shaft 18 rotatably mounted therein which, when the block is in its normal vertical position, is in substantial axial alignment with the shaft 12. A face plate 19 is formed integrally with the inner end of the shaft 18 and a

ring 20 is fixed to the plate 19 so as to enclose the periphery of the roller 14. It will be noted that the bore of the ring 20 is materially larger than the diameter of the roller 14. The purpose of adjustably mounting the bracket 15 is to maintain close alignment between the roller and ring over the full length of the roller.

A pair of arms 21 are formed integrally with the bracket 15 and extend upwardly to substantial vertical alignment with the shaft 18, the arms 10 projecting from the respective ends of the bracket 15. A compression spring 22 is interposed between the ends of the bearing block 17 and these respective arms, the pressure exerted by the springs 22 being adjustable by means of adjusting studs 23.

From the foregoing it will be seen that the bearing block 17 will be urged by the springs 22 in the direction shown by arrow 24 so that the ring 20 will bear against one point on the periphery of the roller 14, as shown in Figure 2. A pair of arms 25 extends upwardly from the opposite side of the bracket 15, the upper ends of which arms 25 have limiting screws 26 threaded therein which limit the swinging movement of the bearing block 17. The screws 26 may be adjusted to maintain a definite clearance between the roller 14 and ring 20 so that should only a small quantity of beans be fed into the machine, the same will not be flattened to an extent greater than the minimum clearance provided. When it is desired to crush the beans to extremely thin flakes, as is required in the extraction of oil therefrom, it may be desirable to loosen the screws 26 so that the ring 20 bears directly against the roller 14. The springs 22 are compressed so that an extremely high pressure will be required to deflect the ring 20 laterally sufficient to allow any but the thinnest of flakes to pass between the roller 14 and the ring 20.

Referring to Figure 4, we have shown diagrammatically means for feeding the beans into the machine and deflecting the flakes therefrom. This mechanism comprises a tube 27 which is interposed between the roller 14 and ring 20 diametrically opposite to the point of contact. The upper end of the tube 27 is connected to a hopper 28. A scraper blade 29 is mounted just below the tube 27 in position between the roller 14 and ring 20 as to form a pair of knife edges which scrape the flaked beans from both of the members should they for any reason tend to adhere thereto. The path the beans take in entering the machine is shown by arrow 29 and that

taken when they are discharged is shown by arrow 30.

In the operation of the machine the pulley 13 is driven between 1500 and 2000 R. P. M. and beans are then fed into the hopper 28. The beans are then conducted to the space between the roller 14 and ring 20. The beans are then carried upwardly by the roller to the position between the roller 14 and ring 20. At this point the beans are rapidly carried downwardly and squeezed to the thickness corresponding to the distance between the roller 14 and ring 20 at the closest point. This distance is controlled to a large extent by the adjustment of the springs 22. The flaked beans are then directed upwardly against the scraper blade 33 which is placed on an angle to eject the flakes along the path shown by arrow 36. Considerable heat is generated in the operation of the machine so that cooling fins 32 are formed on the ring 20.

The chief advantage resulting from the use of our improved machine is that the beans are squeezed over a comparatively large angular rotation of the roller 14 so that reduced power is required to operate the machine.

Some changes may be made in the arrangement, construction, and combination of the various parts of our improved device without departing from the spirit of our invention and it is our intention to cover by our claims such changes as may reasonably be included within the scope thereof.

We claim as our invention:

1. A crusher of the class described comprising a base plate, a pillow block mounted upon said base plate, a driving shaft rotatably mounted in said pillow block, said shaft having a means for rotating same secured to one end thereof and having a roller secured to the other end thereof, a bearing block pivotally mounted upon said base plate adjacent to the roller end of said shaft, said bearing block having a driven shaft rotatably mounted therein in substantial axial alignment with said first mentioned shaft, said bearing

block being pivotally mounted so that said driven shaft may swing in an arc passing through the axis of said driving shaft, a ring member secured to the end of said driven shaft adjacent to said roller, said ring member enclosing the periphery of said roller and having a bore materially larger than the periphery of said roller, a pair of arms extending from said base plate to position adjacent to said bearing block, a compression spring disposed between the upper end of each of said arms and said bearing block to resiliently urge said bearing block laterally so that said ring will bear against said roller at one point around its periphery, and means for feeding the material to be crushed between said roller and said ring at the point of greatest separation therebetween.

2. A crusher of the class described comprising, a base plate, a pillow block mounted upon said base plate, a driving shaft rotatably mounted in said pillow block, a roller formed integrally with one end of said driving shaft, means disposed on the other end of said driving shaft for rotating same, a bearing block having a driven shaft rotatably mounted therein, said bearing block being pivotally mounted upon said base plate so as to swing in such arc that the axis of said driven shaft swings radially toward and from the axis of said driving shaft, a ring fixed to the end of said driven shaft adjacent to said roll, said ring enclosing said roller and having a bore materially larger than the periphery thereof, means for resiliently urging said bearing block laterally so that said ring bears against one point on the periphery of said roller, a tube disposed in the space between said roller and ring at the point of greatest separation therebetween, said tube extending at an angle to the axis of said driving shaft, and a scraper blade fitting the space between said roller and said ring, said blade deflecting the material to be crushed from the space between said roller and ring, for the purpose described.

HENRY FORD.
ROBERT A. BOYER.
